(57) **CLAIM**

The ornamental design for a case and tray for toy beads as shown and described.

DESCRIPTION

FIG. 1 is a front, top and left side perspective view of a case and tray for toy beads showing my new design;

FIG. 2 is a rear, bottom and left side perspective view thereof;

FIG. 3 is a front view thereof;

FIG. 4 is a rear view thereof;

FIG. 5 is a top view thereof;

FIG. 6 is a bottom thereof;

FIG. 7 is a right side view thereof; and,

FIG. 8 is a left side view thereof.

The broken lines in the drawings are for the purpose of illustrating portions of the case and tray for toy beads that form no part of the claimed design.

1 Claim, 8 Drawing Sheets
